US00D936437S

(12) **United States Design Patent** (10) **Patent No.:** **US D936,437 S**
(45) **Date of Patent:** **** Nov. 23, 2021**

(54) **SAW BLADE**

(71) Applicant: **MILWAUKEE ELECTRIC TOOL CORPORATION**, Brookfield, WI (US)

(72) Inventors: **Austin J. Kazda**, Wauwatosa, WI (US);
Robert W. Butzen, Colgate, WI (US);
Andrew J. Schulz, Slinger, WI (US)

(73) Assignee: **Milwaukee Electric Tool Corporation**,
Brookfield, WI (US)

(**) Term: **15 Years**

(21) Appl. No.: **29/738,449**

(22) Filed: **Jun. 17, 2020**

Related U.S. Application Data

(63) Continuation of application No. 15/817,766, filed on Nov. 20, 2017, now Pat. No. 10,722,961, which is a continuation of application No. 14/702,866, filed on May 4, 2015, now Pat. No. 9,827,626, which is a continuation of application No. 13/213,656, filed on Aug. 19, 2011, now abandoned.
